UNITED STATES PATENT OFFICE

2,523,016

GETTER SUPPORTING STRUCTURE

Laszlo U. Hamvas, Schenectady, N. Y., assignor
to General Electric Company, a corporation of
New York

Application December 30, 1948, Serial No. 68,098

2 Claims. (Cl. 250—27.5)

1

My invention relates to an improvement in evacuated electron discharge devices having a getter activated by high frequency induction heating of a closed getter circuit within the device.

After an electron discharge device has been mechanically exhausted, a getter material such as barium is usually flashed or vaporized within the device to clean up the residual gas molecules. It is desirable to control the flashing of the getter by heating it separately with respect to the other elements of the discharge device, this being usually accomplished by passing a heating current through a getter holder consisting of a conducting strip or tubing on or in which the getter material is placed. In discharge devices having a glass envelope the heating current may be induced in a short-circuited getter circuit within the envelope by a high frequency induction coil which is outside of the discharge device envelope. An advantage of this method of flashing the getter is the resulting simplicity of the discharge device itself, as the getter circuit is entirely self-contained and no external terminals are needed.

In apparatus of the character specified, it has been a common practice to form the closed getter circuit by welding a getter holder strip or tubing across the open ends of a U-shaped wire or an incomplete circular wire ring. The loop so formed is customarily welded at one point to the top shield or to a separate supporting element in the electron discharge device to hold the loop in position. The remainder of the getter loop must be spaced from the mount assembly. A disadvantage encountered when the getter loop is welded at one point to the top shield is the lack of an exact predetermined location and position of the getter loop. If this disadvantage is overcome by the use of additional supporting parts or special methods to position the getter loop, the cost of manufacturing the discharge device may thereby be increased.

It is an object of my invention to provide a simplified getter loop structure which utilizes an existing discharge device element as part of the getter loop circuit and thus reduces the cost of manufacture.

A feature of the invention which is useful in accomplishing the foregoing object is an arrangement of the getter circuit wherein two spaced supports secured to the edges of the top shield of an electron discharge device carry the getter holder. In order that the getter may not be prematurely flashed by heat applied to the mount assembly during manufacture, the getter supports are small in cross sectional area as compared with their length, thus minimizing heat conduction from the shield. The same shield surface which acts as a part of the getter loop also serves an additional shielding function by pre-

2

venting the deposition of stray getter material from the getter holder on the electrodes below the shield.

Another aspect of the invention is the integral connection of the getter supports to the top shield, the supports being most easily formed by punching them as tabs when the shield blank is manufactured and bending up the tabs to form the supports. This construction results in a simplified assembly, since no separate getter loop is required, and the getter may be readily assembled in a predetermined position because of the predetermined location of the getter supports.

In another embodiment of my invention which is also useful in fulfilling the foregoing object, I supply a pair of getter supporting strips which are fastened to the edges of the anode in a discharge device of the stacked electrode type, the anode being the uppermost electrode and serving also to shield those electrodes below it from the effects of getter material deposition. The getter holder is fastened to the support strips, forming with the supports and the anode a short-circuited electrically conductive path. The supports are of sufficiently small cross section and of sufficient length to conduct a relatively small amount of heat to the getter from the anode and the other parts of the electrode assembly. By reason of their predetermined location, the getter holder may be easily assembled in the correct position.

The features which I desire to protect herein are pointed out with particularity in the appended claims. The invention itself, together with further objects and advantages thereof, may be best understood by reference to the following description, taken in connection with the drawings in which Fig. 1 is a view partly in cross section showing an electron discharge device embodying my invention; Fig. 2 is an enlarged perspective view of the getter supporting shield shown in Fig. 1; and Fig. 3 is a view partly in cross section showing an electron discharge device embodying a modification of my invention.

Referring now to Fig. 1, there is shown an electron discharge device of a type commonly used in radio receiving tube circuits. As illustrated, an envelope 1 of glass or other suitable vitreous material surrounds an electrode assembly having a plurality of lead-in conductors 2 sealed through the lower end of the envelope. The electrode assembly includes a cathode 3, a grid 4, and an anode 5, and further electrodes may be present as is common in discharge devices of this type. As further shown, a conventional mica spacer 6 holds the upper ends of electrodes 3, 4, and 5 and support rods 7 in a fixed space relationship. Above the top spacer is a metallic shield 8, fastened to the support rods 7 to hold it in place. The shield has a horizontal portion 9 and a ver-

tical portion 10 which are employed in a conventional manner to electrically shield the upper ends of electrodes 3, 4, and 5.

According to my invention and as shown in detail in Fig. 2, two narrow metallic tabs 12 at opposite edges of the horizontal shield portion 9 are bent up vertically and have further end portions 13 bent over horizontally toward each other. The getter holder 14 is positioned on the supporting tabs and its ends welded to portions 13 to hold it securely in place and to form a good electrical connection. The shield may be easily formed by punching out a blank of sheet nickel or other suitable material and bending up the tabs 12 with respect to the horizontal portion 9, further bending over the flanges 13 at the ends of the tabs 12, bending down a portion of this shield to form a vertical shielding portion 10, and bending the ears 11 suitably to facilitate connection to the mount support rods 1. The tabs 12 have a relatively small cross section and are long enough, as illustrated, so that they do not conduct a substantial amount of heat from the electrode assembly to the getter material. I have found that a thin nickel sheet material about .005 inch thick has adequate mechanical strength for this purpose and at the same time its thinness prevents heat conduction from being a problem with respect to premature flashing of the getter.

The getter holder I have shown in Fig. 1 is a strip 14 of conducting metal which, because of its long narrow shape, presents a sufficient resistance to the flow of the induced current to heat the strip to a high temperature along its entire length. A central depressed portion 15 extends almost to the ends of the strip and accommodates an adequate amount of a conventional getter material 16, such as barium or a barium salt mixed with a reducing agent. Of course my invention is not limited to the use of the getter holder illustrated, but obviously includes other getter holders, such as those consisting of a length of iron tubing containing a getter material and clamped together at its ends. In this tubular type of getter holder, as commonly used in the art, a thin portion in the tubing wall bursts when the getter is flashed and the remaining trough, like the recessed holder strip 14 shown in Fig. 1, constitutes a getter shield between the getter and other elements of the tube.

The completed getter supporting structure, without further components, is a short circuited electrically conductive loop, the getter holder 14, the tabs 12, and the shield portion 9 constituting the circuit. After the discharge device is assembled and exhausted a high frequency current is induced in the closed getter circuit by conventional means. The induced current heats the getter holder to a temperature sufficient to start the desired reaction or vaporization of the getter material. The horizontal portion 9 of shield 8 also serves to prevent the deposition of getter material upon the electrodes below it in addition to the usual shielding function of the getter holder itself.

In Fig. 3 is shown another discharge device having a glass envelope 17 with vertically stacked electrodes, the anode 18 being the uppermost electrode in the stock. Annular ceramic disks 19 are used to space the anode and other electrodes from each other. In this embodiment of my invention I employ a pair of sheet metal supports 20 which are welded to the outer edge of the anode 18 at

their lower horizontal ends and are separated from each other by the diameter of the anode. The supports 20 extend above the stacked electrode assembly into the space between the mount assembly and the top of the envelope. A getter holder 21 is welded to the upper ends of the getter supports 19, thus constituting a short circuited electrically conductive loop consisting of the anode 18, the supports 20, and the getter holder 21. It is obvious that, without departing from my invention, that the getter supports 20 may be integrally combined with the anode as tabs on the anode blank.

The getter is flashed as described for the embodiment illustrated in Fig. 1 save that the getter circuit is completed through the anode rather than a shield member. The anode in this embodiment also serves to shield the electrodes below it from effects of stray getter deposition.

In using the term "elements," I means to include both electrodes, such as anodes, and also shields which may or may not serve as electrodes. I recognize, of course, that an electrode such as the anode may also function as a shield.

While the present invention has been described in reference to particular embodiments thereof, it will be understood that numerous modifications may be made by those skilled in the art without actually departing from the invention. I, therefore, aim in the appended claims to cover all such equivalent variations as come within the true spirit and scope of the foregoing disclosure.

What I claim as new and desire to secure by Letters Patent of the United States is:

1. In an evacuated electron discharge device of the type having a vitreous envelope enclosing a plurality of metallic elements, one of said metallic elements constituting an electrical shield for other of said elements, a pair of metallic arms secured to said one of said elements and positioned between said one element and said envelope, and a metallic getter holder connected to said arms and extending therebetween to form therewith and with said one element a short-circuited electrically conductive path, said arms forming paths of low thermal conductivity between said getter holder and said one of said elements.

2. In an evacuated electron discharge device of the type having a vitreous envelope enclosing a plurality of elements including cathode, grid, and anode electrodes and having a plurality of lead-in conductors sealed through the lower end of the envelope, a metallic electrical shield supported in position above the upper ends of said electrodes, a pair of tabs integral with said shield projecting upward from oppositely disposed edges of said shield, and a metallic getter holder connected to said tabs and extending therebetween and forming therewith and with said shield a short-circuited electrically conductive loop, said tabs forming paths of low thermal conductivity between said getter holder and said shield.

LASZLO U. HAMVAS.
